CLAIM

The ornamental design for a computer generated image for a display panel or screen, as shown and described.

DESCRIPTION

FIG. 1 is a front view of a computer generated image for a display panel or screen showing my new design;

FIG. 2 is a front view of a second embodiment;

FIG. 3 is a front view of a third embodiment; and,

FIG. 4 is a front view of a fourth embodiment.

The broken line drawings of a display panel or screen and portions of the image are for illustrative purposes only and form no part of the claimed design.

1 Claim, 4 Drawing Sheets

FIG. 1

FIG. 2

FIG. 3

FIG. 4
